UNITED STATES PATENT OFFICE.

LOUIS GARDNER BOSTEDO, OF ATLANTIC, IOWA.

CASH AND PACKAGE CARRIER.

SPECIFICATION forming part of Letters Patent No. 372,592, dated November 1, 1887.

Application filed April 16, 1887. Serial No. 235,058. (No model.)

To all whom it may concern:

Be it known that I, LOUIS GARDNER BOSTEDO, of Atlantic, in the county of Cass and State of Iowa, have invented certain new and useful Improvements in Locking and Releasing Mechanisms for Cash and Package Carriers; and I do hereby declare the following to be a full, clear, and exact description of the invention, such as will enable others skilled in the art to which it appertains to make and use the same.

This invention relates to an improvement in locking and releasing mechanism for the track-section of the elevator of a cash or package carrier.

In the cash and package carrying system the invention of L. G. Bostedo and H. Thomas, filed November 5, 1886, Serial No. 218,080, two tracks are employed whereon to transmit cash or packages from a clerk's station to a cashier's stand or a bundle-table and return the change or bundles to the starting-point or clerk's station, these tracks being placed one directly above the other, the upper track being preferably employed to dispatch goods or money from a clerk to the cashier or bundle-man, and the lower track to return the wrapped parcel or change from a distant point to the clerk. In this system a car is employed that is raised by an elevator to the lower or upper track, as may be desired. In order to facilitate this operation it is necessary to employ an elevator and an attached track-section, which is made to fit into gaps formed in the lower and upper tracks at a clerk's station, this movable bar or track piece being provided with a locking mechanism to secure the elevator track-section in place to line with either track when it is necessary to dispatch or receive the traveling car, which by its momentum is made to automatically unlock the track-section and elevator in case of an incoming car on a lower track and permit the track-section with the car secured on it to be lowered by the elevator to the hand of the clerk or operator.

The nature and object of my present invention are to improve the mechanism employed to lock and unlock a track-section and render its operation more reliable or perfect, to cause the locking device to be automatically put into

position, to retain the elevator with this track-section in a line with the lower or receiving track by the act of raising the elevator with a car on it to the upper track and dispatching this car, and to automatically release the elevator and its attached track-section when it is in a line with the lower track by the momentum of a moving car and its attached package-carrier arriving from a distant point at a clerk's station, the elevator and car on it being allowed to drop or be lowered to the hand of a receiver by the automatic release or disengagement of the elevator, as stated.

With these objects in view my invention consists in certain features of construction and combinations of parts, that will be hereinafter described, and pointed out in the claims.

Referring to the drawings making a part of this specification, Figure 1 is a front elevation of the track-section and adjacent lower tracks at a clerk's station. Fig. 2 is a front elevation of the upper track ends at a clerk's station with the movable track-section raised and the elevator track-section in position to dispatch a car. Fig. 3 is a rear view of an elevator track-section with my improved locking and releasing mechanism in position on it. Fig. 4 is a plan view of the elevator track-section and the adjacent track to which it is connected or supported to line with. Fig. 5 is a rear elevation of a modified form of elevator track-section locking mechanism.

The improved locking mechanism that constitutes my present invention is applicable to cash-carrier systems other than that of Bostedo and Thomas, and I do not limit myself to its application to the latter-named system; but as it is the present intention to so utilize the device, I will proceed to describe the manner of construction and its adaptation to operate with the Bostedo-Thomas system.

A A are the ends of a lower track at a clerk's station, and B the elevator track-section bar in locked engagement with the track ends. (See Figs. 3 and 4, in which the preferred form of construction is exhibited.)

The body of the track-section bar B is recessed on its front face to receive the operating mechanism, that is already patented to Bostedo and Thomas and that serves to arrest a car on the track-section and store its momen-

tum, to be afterward expended in giving a starting-impulse to an outgoing car on the upper track when the elevator is raised to line its attached track-section with this upper track.

- 5 I will first briefly describe this mechanism. A slot, *i*, is made through the bar *B*, that is parallel with the top and bottom edges of said bar and of sufficient length to afford freedom for the sliding of working parts in the same. o A ratchet-bar, *C*, is placed in the recess cut in the bar *B*. It has its edges cut away to reduce frictional contact. The portions *a a b b* that remain serve as guides to keep the bar in position.

- 5 Integral with the bar *C* the portion *D* is extended at one end and cut with ratchet-teeth on its upper edge, the lower edge having a sliding contact with the flange formed on the bar *B* by a reduction of its body to produce a recess.

The guide-plate *D'* is fixed to the ratchet-bar *C* at right angles to its edges, and has projecting flanges formed on its free edges to hold in place and permit the sliding movement of the engaged ends of the latches *E F*. (See Figs.

- 3 and 4.) The latch *E* is pivoted at *E'* to the ratchet-bar *C*, and, as just stated, its free end is held to slide vertically a short distance, the upward movement being limited by the flange *e* of the bar *B* and its depression by an engagement of the projecting end *e'* with a shoulder formed on the guide-plate *D'*.

Near the pivot end *E'* of the latch *E* a spring, *E'*, is made to bear on its upper edge to cause it to rest with its latch-toe *d* projecting below the lower edge of the bar *B*. The latch *F* is also pivoted to the ratchet-bar *C* at *e* and rests on the studs *e'*, the spring *f* serving to depress the latch when it is raised.

- o An extended arm, *G*, is pivoted at *g* to the bar *B*, and has a toe formed on the end *g'* to engage the ratchet-teeth cut in the bar *C*. The end *h* of the arm *G* is made to extend beyond the termination of the elevator track-section bar *B*, and is intended to have contact with a stud, *h'*, (see Fig. 2,) made to project from the end *A'* of the upper track that is near the gap formed in this track for the reception of the elevator track-section.

- o In Fig. 3 the reverse or rear side of the elevator track-section bar *B* is shown with the locking devices attached, which I shall now describe.

H is a plate that is secured by screws *k* or any proper means to the ratchet-bar *C*, located on the opposite side of the track-section bar *B*, the screws *k* passing through the slot *i* into the ratchet-bar *C*, a liner being introduced or other means employed to permit an easy sliding of these joined pieces on the bar *B*. The plate *H* has an extension, *H'*, made on its top edge to project toward the end of the bar *B*, and is slotted to produce an elongated groove nearly throughout its length. In the rectangular portion of the plate *H* a diagonal slot, *H'*, is cut to extend from the lower edge of the plate on such an incline upwardly toward the

slot in portion *H'* as to intersect it and produce in this way a cam-groove at the inner terminus of the elongated slot. At the lower 70 end of the cam-groove *H'* a short extension of this slot is made to project horizontally.

At each end of the bar *B* the hooks *m* are pivoted to vibrate and extend their hooked ends beyond the bar to engage the studs *m'*, 75 that project from the face of the adjacent track ends *A A* of the lower track.

The **T**-shaped lever *I* is pivoted to the body of the bar *B*, a washer being introduced between the surfaces of the lever and bar to afford a proper clearance of the limbs of the lever and permit the engagement of the longer limb, *o*, with the cam-groove *H'* by a projecting stud that is rigidly affixed to the end of the limb *o* of lever *I* on its inner surface. 85

The **T**-head extensions *n n'* of the lever *I* are made of proper length to give required movement to the connecting-bars *M*, which have their ends *p* pivotally attached to these extensions and their opposite ends affixed at *m'* 90 to the hooks *m*, as shown in Fig. 3 of the drawings.

A spiral spring, *s*, is made to encircle a rod, *s'*, that is secured by one end to the plate *H*, and is extended to enter a supporting box or 95 perforated stud, *t*, which is made to project from the side of the bar *B*, the spring *s* being thus adapted to exert its tensional strength upon the plate *H* when it is compressed and released suddenly. 100

In operation, the elevator with its track-section *B* being in position to line with a lower track, when a car runs upon the elevator track-section a pin that projects from its side engages the latch-toe *d* of the latch *E* and 105 slides the ratchet-bar *C*. This endwise movement compresses the spring *s*, located upon the opposite side of the bar *B*. The teeth of the ratchet-bar *C*, being engaged by the toe *g'* of the arm *G*, will hold this spring compressed; 110 and as this spring acts as a buffer, the car is gently arrested and locked on the elevator track-section by the latches *E F* resuming their normal position.

When a car is arrested and secured, as has just been described, the sliding of the ratchet-bar *C* will cause a corresponding movement of the plate *H*, and in consequence the lever *I* will be vibrated, its engaged limb *o* will be elevated, and the connecting-bars *M* be moved 120 to retract the hooks *m*, thus disengaging them from their contact with the studs *m'* and allowing the elevator and its track-section *B* to descend to the counter or hand of the operator. 125

The provision of the cam grooved and slotted plate *H H'*, with its connected lever *I*, affords peculiar advantages, as it will compensate for the varying momentum given a car by a light or heavy load, and will disengage or unlock the elevator and track-section with a light shock that will cause the arm to rise in the cam-groove in plate *H* to its top, as well as a harder thrust that will so compress the spiral 130

spring s as to make the plate H slide a considerable distance, the engaged end of the lever I traveling in the groove H' of the plate. In either case the hooks m are withdrawn from 5 locked contact with the studs m^2 by the action of the cam-groove in plate H , so that the impact of a heavy-loaded car is absorbed by the spring and a regular reliable action of the unlocking mechanism is assured. When the car is 10 to be dispatched, the elevator, with its attached track-section B , is raised by any proper means to line with an upper or dispatching track. The collision of the extended arm G with a projecting stud on the end of the track will 15 depress this arm and release its toe from the ratchet-teeth of the bar C . The released spiral spring s will exert its energy upon the plate H and attached bar C , causing the car to receive a starting impetus.

20 A further result of the action just described will be the projection of the hooks m beyond the end of the bar B to engage the studs m^2 and hold the track-section and unattached elevator in an aligned position with the lower track 25 to receive a car.

In Fig. 5 a modified form of the locking-bars is shown. In this method of construction the connecting-bars M are simply extended and held in sliding position on the bar B by 30 loops or clips u , which are fastened to this bar. The operation is analogous to that shown in the preferred form of construction, as a retraction of the bars M by the movement of the lever I will withdraw its projecting ends from 35 their bearing-contact upon the studs m^2 and allow the elevator track-section and the attached elevator to descend to the counter, as was shown in the other form of locking mechanism.

40 Slight changes might be made in the details of construction of this device—as, for instance, the connecting-bars shown as locking-bars in Fig. 5 might be slotted near their ends to receive a screw in place of using the loops u to 45 support and retain these bars in place, and instead of using a slotted extension, H' , and the cam-groove in plate H a bar or wire might be substituted to take the place of the slotted groove, and a swivel-box be fixed upon the 50 limb of the T -headed lever I to slide on this wire or bent guide-rod, and thus obtain the same results afforded by the cam-grooved plate and stud sliding in it.

Other slight modifications might be made 55 in the constructive details of this device without departure from its spirit and legitimate scope; hence I do not wish to restrict myself to exact forms shown; but,

Having fully described my invention, what 60 I claim as new, and desire to secure by Letters Patent, is—

1. In a locking and releasing device for the

elevator track-section of a car and package carrier, the combination, with a track-section bar, of a pivoted lever engaging a cam-grooved 65 plate and two connecting-bars, the said lever adapted to move the bars to lock or release the elevator track-section, substantially as set forth.

2. In an elevator track section bar, the combination, with a track-bar, of a pivoted T -shaped lever, a cam-grooved plate having a straight slotted extension, two connecting-bars pivoted to the T -lever, and two pivoted hooks loosely attached to the connecting-bars, sub- 75 stantially as set forth.

3. In an elevator track-section, the combination, with a track-bar, a cam grooved plate mounted thereon, and an elongated slotted extension of the cam-grooved plate, of a T -headed 80 pivoted lever having one of its limbs in sliding engagement with the cam-groove in the grooved and slotted plate, two connecting-bars pivoted to the T -headed lever, and a spiral spring to move the parts, substantially as set forth.

4. In an elevator track section bar, the combination of a track-bar, a cam-grooved plate having a slotted extension at one side, a T headed lever pivoted to the track-bar and having one of its limbs in sliding engagement 90 with the cam grooved and slotted plate, two connecting-bars pivoted to the T -head of this lever, and hooks pivoted to the track-bar and loosely connected to the connecting-bars, substantially as set forth.

5. In an elevator track-section bar, the combination of a slotted track-bar, a cam-grooved plate adapted to slide on the bar and secured through the slot to a ratchet-bar located on the opposite side of the bar, a T -headed lever engaging the cam-grooved plate, two connecting-bars pivoted to the T -headed lever, two hooks pivoted to the track-bar and loosely secured to the connecting-bars, and a spiral spring to move the cam-grooved plate, 105 hooks, and ratchet-bar, substantially as set forth.

6. In an elevator track-section bar, the combination, with a track-bar slotted longitudinally, a ratchet-bar, an extended arm, and two 110 pivoted and spring-actuated latches, of a cam grooved and slotted plate secured through the slot in the track-bar to the ratchet-bar, a T -headed lever, two connecting-bars, two hooks, and a spiral spring, substantially as 115 set forth.

In testimony whereof I have signed this specification in the presence of two subscribing witnesses.

LOUIS GARDNER BOSTEDO.
